UNITED STATES PATENT OFFICE.

WILLIAM ALBERT BANISTER AND DAVID M. LAKE, OF NEWARK,
NEW JERSEY.

INDICATOR.

No. 857,857.

Specification of Letters Patent.

Patented June 25, 1907.

Application filed February 27, 1907. Serial No. 359,637.

To all whom it may concern:

Be it known that we, WILLIAM ALBERT BANISTER and DAVID M. LAKE, citizens of the United States, residing at Newark, in the county of Essex and State of New Jersey, have invented certain new and useful Improvements in Indicators; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention is designed to provide an indicator, and has been designed particularly for displaying the numbers on automobile vehicles, the function of the device being to prevent the numbers being obstructed by dust and dirt, this being accomplished by providing a moving cover that, in its movement, is being continually wiped or brushed to keep it clean.

The device is also provided with a hollow casing in which the rotating cover is installed, and within which is also arranged the number, the number being adapted to have a light shine through from the interior of the casing, to make the numeral plain in the dark.

The device is adapted for lighting by either electricity or a fuel consuming light, and to this end the article is also-constructed to provide a reservoir for oil or similar illuminant.

The device is illustrated in the accompanying drawing, in which

Figure 1 is a view showing the machine in elevation in one part of the view, and being broken away at the other to show the interior construction. Fig. 2 is a cross-section of the apparatus.

In our device we employ a casing 10 which can be provided with a suitable cover or lid

11. Secured to the casing 10 and projecting longitudinally therethrough, is a support 12, which support can be used to hold suitable electric lights 13, or acetylene gas or kerosene can be used, in which case the support 12 is used as a reservoir. In front of the light is a panel 14 which is preferably made of ground glass, or a similar opalescent material, and on

this panel is painted the number or the device 15 that is to be displayed. This panel is held, at the bottom, on the support 12, and on the top by a shield 16 which is open at one

end 17, and is provided, in its bottom, with 55 slots 18 to provide ventilation or draft when an oil lamp is used. Surrounding the support, the panel and the flue, above described, is a cylinder 19 which can be made of glass or quartz, or any transparent material, 60 and rests on one end on the rollers 20, although equivalent devices can be installed for these purposes. On the other end we prefer to fasten the plate 21 to the transparent cylinder 19, this plate 21 having a projecting shaft 22 which runs in a bearing 23 in the side of the casing 10, and suitable driving mechanism 24 is installed to rotate the transparent cylinder.

When an oil lamp is used for an illuminant, 70 it is necessary to provide a draft, and when the flue formed by the shield 16 is not sufficient, the flange 21 can be provided with suitable openings 25, and the casing 10 can be perforated as at 26. When electric light is 75 used, however, these openings can all be dispensed with. Bearing on the transparent cylinder 19, and inside the casing, is a wiping roller 27 which can be actuated by the cylinder 19, or can be otherwise rotated. Directly 80 underneath the opening in the front of the casing 10, through which a portion of the glass cylinder projects, is a cross rod 28 on which is pivoted a suitable leaf 29 which is constantly forced upward by the action of the 85 spring 30, and a wiper 31, which can be made of any suitable material, but is preferably constructed of a rubber strip, constantly wipes the dust and the dirt from the transparent cylinder, and in the case of automobiles 90 this wiping makes it possible to see the letters, or the numbers indicating what machine it is, very distinctly, at all times, which is not possible now on dusty roads where the usual license tag becomes dirty and every- 95 thing appears brown.

The wiping cylinder 27 is preferably covered with felt, and also assists in keeping the transparent cylinder polished and clean. The transparent cylinder in the day time 100 does not at all interfere with a ready reading of the numbers, and the light behind the panel with the numbers on it, allows the numbers to be plainly read at night.

Having thus described our invention, 105 what we claim is:—

1. An indicator comprising a casing having a legend therein, a rotating transparent

cylinder passing over the legend, and a wiper to clean the cylinder as it rotates.

2. An indicator comprising a panel, a transparent movable cover for the panel, and 5 a wiper to wipe the cover when it moves.

3. An indicator comprising a casing, an opalescent panel, a transparent cylinder inclosing the panel and projecting from the casing, means for rotating the cylinder, and 10 a wiper installed to wipe the cylinder when it is rotated.

4. An indicator comprising a casing having lights therein, a support for the lights secured to the casing, a flue above the lights 15 and leading to the outside of the casing, a panel within the casing, a transparent cylinder within the casing and projecting slightly therefrom and inclosing the flue, the panel and the support, means for rotating the cylinder, and a wiping device in engagement with 20 the transparent cylinder.

5. An indicator comprising a casing, a support therein, lamps on the support, a shield above the lamps and communicating with 25 the atmosphere, a panel secured in front of

the lights and between the shield and the support, a transparent cylinder inclosing the lights and the panel, a wiping roll within the casing and engaging the cylinder, means for rotating the cylinder, and a wiping device in 30 the casing and in engagement with the transparent cylinder.

6. An indicator comprising an indicating device, a transparent cylinder surrounding the same, means for rotating the cylinder, a 35 casing for supporting the cylinder, a shaft in the casing, a pivoted leaf on the shaft, a spring between the leaf and the casing to normally throw the leaf toward the cylinder, and a wiping strip on the end of the leaf and 40 in engagement with the cylinder.

In testimony, that we claim the foregoing, we have hereunto set our hands this 26th day of February 1907.

WILLIAM ALBERT BANISTER.
DAVID M. LAKE.
